UNITED STATES PATENT OFFICE

172,088

TELEVISION FOCUSING GLASS

Edward F. Coleman and Homer H. Lackey, Jr.,
Lynchburg, Va.

Application September 2, 1953, Serial No. 26,672

Term of patent 7 years

(Cl. D57—1)

To all whom it may concern:

Be it known that we, Edward F. Coleman and Homer H. Lackey, Jr., both citizens of the United States and residents of Lynchburg, State of Virginia, whose Post Office addresses are respectively 508 Elwood Avenue and 3801 Cambria Street, Lynchburg, Virginia, have invented a new, original, and ornamental Design for a Television Focusing Glass, of which the following is a specification, reference being had to the accompanying drawings, showing our new design, forming part thereof.

Figure 1 is a front elevational view of a television focusing glass, showing our new design;

Figure 2 is a rear elevational view thereof; and Figure 3 is a side elevational view thereof

showing the handle in a forwardly adjusted position.

We claim:

The ornamental design for a television focusing glass, as shown.
